SUBMARINE RESCUE AND ESCAPE
MECHANISM

Carroll D. Pleak, Greensburg, Ind.

Application February 12, 1940, Serial No. 318,442

3 Claims. (Cl. 114—16.5)

The present invention relates to submarine rescue and escape mechanism, and the primary object of the invention is to provide mechanism, carried upon a submarine vessel, and operable entirely from within the vessel, whereby the crew may escape to the surface from a disabled submarine, and whereby a buoy may be projected to the surface, carrying with it signalling mechanism and means whereby air may be pumped from the surface to the submarine, whereby telephone communication can be established with the surface, and whereby electrical power may be conducted from the surface to the submarine for use aboard the disabled vessel. Further objects of the invention will appear as 15 the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a transverse section, more or less diagrammatic, through a submarine, showing the arrangement of my rescue buoy and my escape car and the operating mechanism therefor;

Fig. 2 is a horizontal section taken substantially on the line 2—2 of Fig. 1 and looking in the direction of the arrow, the buoy and car having been removed for clarity of illustration;

Fig. 3 is an enlarged transverse section showing the manner of connection of the rescue conduit with its reel;

Fig. 4 is a top plan view of my rescue buoy in inflated condition;

Fig. 5 is a side elevation thereof;

Fig. 6 is an enlarged vertical section through the gas reservoir forming a part of my buoy;

Fig. 7 is an enlarged sectional view of a valve used in connection with the gas reservoir;

Fig. 8 is an enlarged sectional view of connector means for the conduit;

Fig. 9 is an end view of the connector head at the end of the conduit;

Fig. 10 is an enlarged elevation of the buoy-ejecting means of my invention;

Fig. 11 is an enlarged fragmental sectional view of the water-tight seal formed between the escape car and the upper portion of its compartment;

Fig. 12 is a more or less diagrammatic view of the reel for the rescue conduit and its driving means; and

Fig. 13 is a similar view of the reel for the escape car cable and its driving means.

The numerous tragedies which have resulted from disablement of submarine vessels while submerged, have been due primarily to the fact that no efficient means has been provided heretofore for permitting the escape of the crew of the disabled vessel. The rescue bell which has recently come into use is marvelously effective once it is properly attached to the disabled vessel, but, unless all of the circumstances surrounding the vessel are perfect, the bell cannot be attached to the submarine without the services of divers; and often submarine vessels are disabled at a depth such as to make diving impossible. The escape lung is also effective in many cases; but it cannot be used beyond relatively shallow depths, its use subjects the crew members to submersion in water which may be impossibly cold, and it also subjects the users to water pressure which may be highly injurious, and which certainly will be injurious unless the users rise through the water relatively slowly.

When a submarine is disabled while submerged, it sometimes happens that the circumstances are such that if sufficient electric power could be supplied to the vessel from an outside source, the vessel could be raised. At other times, the circumstances are such that, if suf-

20 25 30 35 40 45 50 55

ficient air could be supplied to the disabled vessel, it would be possible for the crew to make necessary repairs and bring the vessel to the surface.

In attempting to overcome all of these defects of prior art mechanisms and to provide means whereby air and electric power can be supplied to the disabled vessel from an assisting vessel on the surface, I have conceived the mechanism of the present application.

In the drawings, the hull of a submarine vessel is indicated generally by the reference numeral 20. All such vessels are provided with a plurality of transverse bulkheads at spaced locations throughout the length of the vessel; and such a bulkhead is indicated at 21. In the interest of both space economy and safety, I propose to build my escape and rescue mechanism into one or more of these bulkheads; and in Fig. 2, I have shown how this can be done. The longitudinal depth of the bulkhead is increased as at 22 by providing walls 23 and 24 to form a room 25 communicating with the body of the vessel through doors 26 and 27. All of the controls for the mechanism of the present invention are accessible from within the room 25; so that, even if a part of the

vessel is flooded, the doors 26 and 27, or that one of those doors which is adjacent the flooded portion of the vessel, may be closed to prevent flooding of the room 25, and so that the rescue and escape mechanism of the present invention may be operated from the protected room.

A door 28, which is water-tight when closed, provides access from the room 25 to a water-tight chamber 29 having a long, vertical, cylindrical portion 30 which opens at 31 through an outer wall of the vessel. The port 31 is normally closed by a hatch 32 of standard and well known construction which may be locked, unlocked, and removed by any known mechanism for so manipulating hatches. Within the chamber 29 is 15 mounted a reel 33 upon which is wound a flexible, but armored, conduit 34. The reel 33 is preferably connected to be driven by an electric motor 35, through a gear reduction 36; and one end of the conduit 34 is suitably connected to my rescue buoy indicated generally by the reference numeral 37 in Fig. 1, said buoy being normally carried in the cylindrical portion 30 of the chamber 29.

The reel 33 comprises a hollow shaft 38 which carries an elbow 39, shown in Fig. 12 and in detail in Fig. 3. The conduit 34 is formed at its opposite ends with connector heads 40 and 44. The head 40 cooperates with a connector head 41 on a long tubular element 42 forming a part of the buoy, and may be secured thereto by any suitable coupling means such as the swiveled coupler 43. The head 44 is similarly connected to the elbow 39 through any suitable means such as the swiveled coupler 45. The conduit 34 is formed to provide an air passage 46, an electric power line 47, a telephone line 48, and any other desired conductors, extending from end to end thereof. The elbow 39 and the head 44 are formed with cooperating connector elements similar to the elements 151, 152, 153, 154, and 155 of Fig. 8, whereby, when the head 44 is brought into cooperative relationship with the elbow 39, operative connections will be established between the gas passage 46 of the conduit and the gas-carrying tube 46' in the elbow, between the power line 47 of the conduit and the power line 49 of the elbow, and between the telephone line 50 of the conduit and the telephone line 50' of the elbow. As is clearly shown in Fig. 12, the conductors 46', 49, and 50 extend axially through the shaft 38, and are operatively connected through a standard swivel coupler to stationary conductor lines (not shown). The power and telephone lines will be continued to a central switch board, the controls of which will be accessible in the room 25, and the air conduit will be continued, through valved pipes, to distribute air to desired portions of the vessel.

Corresponding conductors 148, 149, and 150 extend throughout the length of the tube 42, terminating in a coupler head 51, similar to the head 41, at the uppermost end of the tube 42.

The tube 42 forms a supporting base for the buoy 37 and for the gas reservoir indicated generally by the reference numeral 52 and illustrated in detail in Fig. 6. Said reservoir comprises a cylindrical shell 53 within which are fixed upper head 54 and lower head 55, said heads being secured likewise to a central sleeve 56 which is sleeved in place on the tube 42. A base 57, having a plurality of ports 58 therethrough, supports the reservoir in position on the tube 42; and said base is formed with a radially extending annular flange 59 for a purpose later to be described. At the upper end of the shell 53, there is provided an

annular shoulder 60, the purpose of which also will be described hereinafter.

It will be seen that the base 57 cooperates with the head 55 to provide a chamber 61 open to the circumambient medium; and the reason for this will appear hereinafter. A nut 62 secures the reservoir assembly in place on the tube 42.

A bracket 63 is sleeved in place on the tube 42 immediately above the reservoir 52, said bracket and reservoir being provided with cooperating elements 64 to prevent relative rotation thereof. The bracket 63 is provided with an upstanding flange 63' to which is secured the lower end of an air-tight bag 66 which should be formed of any available air-tight material capable of being readily folded and collapsed. I prefer to form the bag 66 of material which is non-elastic; but the essential characteristics of the material are that it shall be air-tight, unaffected by sea water, readily foldable, tough, and of high tensile strength. The lower end of the bag is secured to the flange 63' by means of a band 67 held in place on said flange by a plurality of bolts 68, or the like; and of course the joint must be air tight.

It will be noted that the upper end of the shell 52 terminates short of the bracket 63, leaving a space 69 therebetween, and defining a chamber 70 open to the circumambient medium.

Referring, now, to Figs. 4 and 5, it will be seen that the bag 66, when in inflated condition, is surrounded by a protecting shield consisting of a plurality of toggle elements. When deflated and collapsed, the bag 66 is much more closely surrounded by the said toggle elements, as is apparent from an inspection of Fig. 1.

Adjacent the upper end of the tube 42 there is secured in place a bracket 71, the same being held in place by a nut 72 or the like. A plurality of bars or shield elements 73 are pivotally secured to a like number of radially projecting arms 74 upon the bracket 71, said shield elements 73 being mounted upon pivots 75, the axes of which lie in planes substantially perpendicular to the axis of the tube 42, and are arranged in an annular series.

Slidably mounted upon the shell 52 is a second bracket 76 formed to provide a plurality of radially extending arms 77 carrying pivots 78, said pivots being arranged upon axes lying in planes substantially parallel with the planes of the pivots 75. A coiled spring 79 surrounds the shell 52, is supported on the flange 59, and constantly urges the bracket 76 upwardly toward engagement with the flange 60. A plurality of shield elements 80, similar to the elements 73, are pivotally mounted on the pivots 78; and the free ends of the elements 80 are hingedly connected to the free ends of the corresponding elements 73 by hinge means 81, or the like.

Obviously, if the bracket 76 is pressed downwardly against the tendency of the spring 79, the shell elements 73 and 80 will be straightened and brought into the positions of Fig. 1, while the bag 66 will be collapsed. However, when the bracket 76 and the shield elements are released, the spring 79 will force the bracket 76 upwardly to the position of Fig. 5, thereby expanding the shield elements.

Suitable latch means (not shown) may be provided for holding the bracket 76 in its lowermost position; and if such means is used, the latch must be released before the buoy is ejected from the vessel, such release being effected either man-

ually or by automatic means such as a pawl adjacent the mouth 31 of the chamber 30.

However, such latch means is not essential; since the shield elements will be held in their straightened position, whenever the buoy is in the chamber 30, by engagement with the walls of that chamber; in which case, the force of the spring 79 will tend to assist in the ejection of the buoy after the hinges 31 have passed the mouth 31 of the chamber 30.

Returning to Fig. 6, it will be seen that there is positioned in the chamber 61 a pressure-responsive instrument 82 which may be either a diaphragm or a bellows or a piston. Such element 82, however, supports a column of liquid in a pipe 84 extending upwardly through the head 55, into the reservoir, and communicating with the lower portion 85 of a pressure-responsive valve indicated generally by the reference numeral 86. A hand-operated valve 83, normally in closed position, prevents movements of the pressure-responsive element 82 from being communicated to the valve 86 under normal conditions.

Valve 86 is provided with a port 87 constantly in open communication with the interior of the reservoir 52 in which is contained air or other gas under very high pressure. A pipe 88 leads from the outlet port of the valve 86 through the head 54, through the chamber 70, and through the bracket 63, to the interior of the bag 66. Another pipe 89 leads from the interior of the bag 66 to the upper end 90 of the valve 83. Within the valve housing is reciprocably mounted a piston-type valve 91 formed with heads 92 and 93 respectively received in the lower and upper parts of the valve housing, and formed with a passage 94 which, in one position of the valve, will establish communication between the port 87 and the pipe 88.

It will be seen that the head 92 is larger than the head 93, and that the pressure of the circumambient medium is impressed upon the head 92 whenever the valve 83 is open, while the pressure within the bag 66 is impressed at all times upon the head 93.

One form of valve which may be used at 83 is illustrated in Fig. 7. As illustrated, such valve may comprise a casing 95 having a passage 96 therethrough, and formed with an intersecting frusto-conical socket 97 in which is received a correspondingly-shaped valve head 98 formed with a passage 99 therethrough. A stem 100 is connected to the valve head 98 and may be provided with an operating handle 101 readily accessible to the operator, as shown in Fig. 6.

An escape valve 102 provides a controlled passage from the interior of the bag 66 to the chamber 70 through the port 103 and the port 104. A valve member 105 controls such flow, being reciprocably mounted in the case 102 and being formed with a passage 106 registerable in one position, with the port 104. A port 107 places the lower end of the valve member 105 in open communication with the circumambient medium in the chamber 70, and the upper end of said valve member is always in open communication with the gas in the bag 66. A spring 108 tends to hold the valve member 105 in the position illustrated in Fig. 6.

Means must be provided for flooding the chamber 29 and its extension 30, since the pressures on opposite sides of the hatch 32 must be substantially equalized before the hatch can be opened. In Figs. 1 and 2 I have illustrated a pipe

109 leading from the exterior of the vessel to the chamber 29, a valve 110, accessible from within the room 25, provided to control flow through said pipe.

- 5 Although, once the chamber 29, 30 is flooded and the hatch 32 is removed, the buoy 37 will tend to float out of the chamber 30, I prefer to provide mechanical means for positively ejecting the buoy. Such means comprises a yoke 111, 10 illustrated in Figs. 1 and 10, immediately subjacent the flange 59, and a push rod 112 operatively associated therewith. As is clearly shown, said push rod is provided with rack teeth 113 and is mounted to slide through a gear box 114 in 15 which is positioned a pinion 115 carried on a shaft 116 rotatable by a hand wheel 117 accessible from within the room 25.

In case of an emergency, the door 23 is opened and the handle 101 is rotated through 90° to 20 place the pressure-responsive element 82 in control of the liquid column in the pipe 84. Immediately, the pressure of air upon the pressure-responsive element 82 will be communicated to the head 92. Since the effective area of the head 92 is greater than the effective area of the head 93, and since the pressures existing in the chamber 61 and within the bag 66 are equal, the valve 81 will be raised to bring the passage 94 into registry with the conduit 88. It will be noted that the passage 94 is small, so that air flow, even though the pressure within the reservoir 52 is very high, will be gradual. Immediately after opening valve 83, the door 23 is closed and sealed and the valve 110 is opened to flood the chamber 29, 30. As soon as the pressure within the chamber 29, 30 substantially equals the pressure upon the outer surface of the hatch 32, the hatch 32 is removed by standard operating means and the hand wheel 117 is operated to eject the buoy 37.

- 40 As the buoy 37 leaves the chamber 30, the spring 79 forces the bracket 76 upwardly, thereby expanding the shield which, until that time, has acted to prevent the bag 66 from scraping against the surfaces of the chamber 30.
- 45 Meantime, air is flowing into the bag 66. The pressure now impressed upon the element 82 is the pressure of the surrounding water; so that air will continue to flow into the bag 66 from the reservoir 52 until the pressure within the bag 50 somewhat exceeds the outside water pressure, whereupon the effective pressure upon the head 93 will exceed the effective pressure upon the head 92 to return the valve 81 to the position of Fig. 6. While the differential between pressure 55 within the bag and the water pressure may be any reasonable predetermined amount, I prefer to proportion the parts so that the valve 91 will be returned to the position illustrated in Fig. 6 when the pressure within the bag 66 exceeds the water pressure by approximately eight pounds per square inch.

The bag 66 is so proportioned that it will readily lift the weight of the amount of conduit 34 carried aboard the vessel. If desired, and in 60 order to assist the rise of the buoy, the motor 35 may be operated during the rise of the buoy to rotate the reel 33 to feed the conduit to the buoy.

Obviously, if the vessel rests upon the bottom at a level such that the water pressure is two 65 hundred pounds per square inch, and if a pressure of two hundred and eight pounds per square inch is charged into the bag, the rupturing pressure upon the bag is only eight pounds per square inch. If the buoy were permitted to rise to the surface, however, without valving air out of the

bag, the rupturing pressure of the gas within the bag would become one hundred and ninety-three pounds per square inch; and it is impractical to provide a bag made of material capable of withstanding such a rupturing pressure. It is for this reason that I have provided the valve mechanism 102—109.

As has been stated, the spring 108 tends to hold the valve member 105 in the position of Fig. 6, as does also the pressure of the circumambient medium. The pressure within the bag, however, tends to move the valve member 105 in a direction to bring the passage 106 into registry with the port 104. I prefer so to proportion the spring 108 that the valve will be moved to exhaust position when the pressure within the bag exceeds the pressure of the circumambient medium by a value slightly greater than the pressure differential which will close the valve 91; for instance, ten pounds. Thus, if we again assume that the buoy is released at a point at which the water pressure is two hundred pounds per square inch, it will be seen that the valve 105 remains in closed position until after the valve 91 is closed. As the buoy rises, the water pressure will decrease. If gas has been charged into the bag to a pressure of two hundred and eight pounds per square inch, the valve 105 will remain closed until the buoy has reached a position at which the circumambient pressure is ninety-eight pounds, whereupon the valve 105 will open to discharge some air from the bag. If it be assumed that everything is perfectly air-tight, it will be clear that the valve 91 will not again be opened as the buoy rises, but that the valve 105 will be periodically opened, or that it may remain open throughout the rise of the buoy, to prevent the pressure differential between the inside and the outside of the bag 66 from rising beyond ten pounds per square inch; so that, when the buoy reaches the surface, the pressure within the bag will be twenty-five pounds per square inch.

However, if leakage should occur, so that the pressure differential between the inside and the outside of the bag should drop to a value less than eight pounds per square inch, the valve 91 will again be opened to replenish the supply of air within the bag and to raise the pressure differential again to the eight pound value for which the valve 91 is set.

Obviously, the buoy 37 may carry any kind of signalling devices, such as lights, bells, whistles, or radio broadcasting aerials; but the particular details of such signalling mechanisms form no part of the present invention. Once the buoy is located, however, by a rescue ship, which may be provided with a conduit similar to the conduit 34, that conduit may be connected, by the rescue ship, to the head 51; thereby establishing a contact with the disabled vessel through which air may be pumped to the vessel, through which telephone communication is established, and through which electric power may be conducted to the disabled vessel.

In a second water-tight compartment 118 there is located a reel 119 upon which is wound a cable 120. Within a cylindrical, vertical extension 121 of the chamber 118, there is positioned an escape car 124. The extension 121 opens at 122 through an upper wall of the vessel, and the opening 122 is closed by a hatch 123 of standard construction.

The car 124 is provided with an exit opening 125 in its upper end, closed by a hatch 126 of standard construction and operable from either inside the car or outside the car; and with an

entrance opening 127 in its lower portion, provided with a hatch 128 of standard construction operable either from the inside or the outside of the car. The car may be provided with seats 129, if desired.

Projecting downwardly below the port 127 is a spider 130 terminating in a collar 131, or the like, to which is securely fastened an end of the cable 120.

10 The car 124 and the compartment extension 121 are formed with cooperating surfaces providing a water-tight joint 132, the details of which are illustrated in Fig. 11. As there shown, the compartment wall is formed to provide an upwardly facing annular shoulder 133 bounded at its inner edge by a flange 134. A compressible washer 135 may be positioned in the channel 133; and the upper portion of the car 124 is formed to provide a downwardly facing channel 136 receiving the upper edge of the flange 134 and a downwardly facing lip 137 adapted to engage and compress the washer 135. It will be obvious that, when the car 124 is pulled tightly down against the seal 132, these cooperating surfaces will prevent the flow of water into the lower portions of the compartment 118, 121.

15 A door 138 provides access from the room 25 into the compartment 118, and a platform 139 is located immediately below that door, providing a support for a person seeking entrance to the car 124. A conduit 140 leads from the outside of the vessel and communicates with a pipe 141, controlled by a valve 142, and leading into the chamber 143 between the seal 132 and the hatch 123. The conduit 140 also communicates with a pipe 144 controlled by a valve 145 and leading into the compartment 118. The door 138, valve 142, and valve 145 are all accessible from within the room 25.

20 When it is desired to use the escape car, the space 143 is flooded by opening the valve 142, and the hatch 123 is thereupon removed. The door 138 and the hatch 128 are now opened and one or more men crawl into the escape car and lock the hatch 128. The valve 145 is now opened to flood the compartment 118, 121; and as soon as that compartment is flooded, the escape car 124 will float out of the compartment and to the surface. Assuming the presence of a rescue

25 ship, the hatch 126 is removed, the passengers leave the car, and the hatch 126 is again secured. The crew aboard the disabled vessel is now notified by telephone that the car is ready for its return trip, and the motor 146, connected to the reel 119 through a reduction gear 147, is operated to drive the reel 119 to haul in the cable 120. As the car reaches the vessel, it is necessarily centered by the cable upon the opening 122, and is pulled into sealing engagement with the seal 132.

30 Thereupon the door 138 is opened, whereby the compartment 121 will be emptied down to the level of the bottom of the door. True, a certain amount of water will thereby be discharged into the room 25; but it will be a relatively small amount, since all of the water below the door 138 will be retained in the compartment 118.

35 Of course, this partial draining of the compartment 121 will create an enormous pressure differential which will hold the car 124 in sealing engagement with the washer 135.

40 This operation is repeated until all crew members have escaped from the disabled vessel.

45 I claim as my invention:

50 1. A distress signalling mechanism for sub-

marines comprising a collapsible buoy adapted to be carried on a vessel in collapsed condition, a reservoir containing a compressed gas, said reservoir being carried on said buoy, conduit means providing communication between said reservoir and the interior of said buoy, valve means controlling flow through said conduit means and comprising an element having a surface subject to the pressure currently existing in the interior of said buoy and having a larger opposing surface subject to the current pressure of the circumambient medium, said element being movable, under the joint effect of a pressure within the buoy exceeding the pressure of such medium by less than a predetermined value, to open said valve means to permit flow through said conduit, and movable to close said valve means whenever the pressure within said buoy exceeds the pressure of said medium by more than such predetermined value, and a second valve means controlling communication between the interior of said buoy and the circumambient medium, and comprising an element having a surface subject to the pressure currently existing in the interior of said buoy and an opposing surface subject to the current pressure of such circumambient medium, and movable under the joint effect of a pressure within the buoy exceeding the pressure of such medium by more than a predetermined value, to open said second valve means, but movable to close said second valve means whenever the pressure within said buoy exceeds the pressure of such medium by less than such last-mentioned predetermined value.

2. A distress signalling mechanism for submarines comprising a collapsible buoy adapted to be carried on a vessel in collapsed condition, a reservoir containing a compressed gas, said reservoir being carried on said buoy, conduit means providing communication between said reservoir and the interior of said buoy, valve means controlling flow through said conduit means and comprising an element having a surface subject to the pressure currently existing in the interior of said buoy and having a larger opposing surface subject to the current pressure of the circumambient medium, said element being movable, under the joint effect of a pressure within the buoy exceeding the pressure of such medium by less than a predetermined value, to open said valve means to permit flow through said conduit, and movable to close said valve means whenever the pressure within said buoy exceeds the pressure of said

medium by more than such predetermined value, and a second valve means controlling communication between the interior of said buoy and the circumambient medium, comprising an element having a surface subject to the pressure currently existing in the interior of said buoy and an opposing surface subject to the current pressure of such circumambient medium, and movable, under the joint effect of a pressure within the buoy exceeding the pressure of such medium by more than a predetermined value higher than said first-mentioned predetermined value, to open said second valve means, but movable to close said second valve means whenever the pressure within said buoy exceeds the pressure of such medium by less than such last-mentioned predetermined value.

3. A distress signalling mechanism for submarines comprising a collapsible buoy adapted to be carried on a vessel in collapsed condition, a reservoir containing a compressed gas, conduit means providing communication between said reservoir and the interior of said buoy, valve means controlling flow through said conduit means and comprising an element having a surface subject to the pressure currently existing in the interior of said buoy and having a larger opposing surface subject to the current pressure of the circumambient medium, said element being movable, under the joint effect of a pressure within the buoy exceeding the pressure of such medium by less than a predetermined value, to open said valve means to permit flow through said conduit, and movable to close said valve means whenever the pressure within said buoy exceeds the pressure of said medium by more than such predetermined value, and a second valve means controlling communication between the interior of said buoy and the circumambient medium, and comprising an element having a surface subject to the pressure currently existing in the interior of said buoy and an opposing surface subject to the current pressure of such circumambient medium, means biasing said second valve means toward closed position, and said element being movable, under the joint effect of a pressure within the buoy exceeding the pressure of said medium by more than a predetermined value, to open said second valve means, but movable to close said second valve means whenever the pressure within said buoy exceeds the pressure of such medium by less than such last-mentioned predetermined value.

CARROLL D. PLEAK.
